COMPOSITIONS COMPRISING SOLID SOLUTIONS OF CHLORINATED PARAFFIN AND GAMMA BENZENE HEXACHLORIDE

Hyett Henry Spendlove, Bovingdon, Maidenhead, and Alastair Campbell, Widnes, England, assignors to Imperial Chemical Industries Limited, London, England, a corporation of Great Britain

No Drawing. Filed Nov. 19, 1958, Ser. No. 774,837
Claims priority, application Great Britain Dec. 2, 1957
9 Claims. (Cl. 167—42)

The present invention relates to improvements in or relating to compositions comprising benzene hexachloride and more particularly to water dispersible pesticidal pulverulent compositions comprising gamma benzene hexachloride.

A known disadvantage of gamma benzene hexachloride is that the pesticidal activity of its deposits may not be sufficiently persistent and to overcome this defect compositions comprising for instance gamma benzene hexachloride and one or more fusible materials solid at room temperature and having a lower vapour pressure than the hexachlorocyclohexane have been proposed and in order to show that these compositions give deposits which are more persistent in their pesticidal activity than compositions of the same percentage strength of gamma benzene hexachloride which do not contain any of the aforesaid fusible material, Petri dishes have been employed as deposition surfaces.

It has been experimentally ascertained however that although, for example, by spraying solutions containing 2 parts of coumarone resin to one part of gamma benzene hexachloride, more persistent deposits are obtained on non-absorbent surfaces than solutions containing gamma benzene hexachloride alone there is no increase in persistence on absorbent surfaces. It is however on such surfaces as that of lateritic mud, which is the material used in some tropical regions for building mud huts, that much antimalarial spraying is carried out.

The object of the present invention is to provide water dispersible pesticidal pulverulent compositions comprising gamma benzene hexachloride which when deposited as by spraying of their water dispersions on sorptive and non sorptive surfaces give deposits which have a more persistent pesticidal activity than heretofore.

It has now been found that deposits of improved pesticidal persistency can be formed on sorptive and non sorptive surfaces from water dispersible pesticidal pulverulent compositions comprising an admixture containing gamma benzene hexachloride and at least one resin in intimate association wherein the ratio of gamma benzene hexachloride to resin is such that for vapour pressures measured by effusion at 50° C. the vapor pressure of the gamma benzene hexachloride is less than 75% of the vapour pressure of free gamma benzene hexachloride and after 25% has evaporated at 50° C. the vapour pressure is less than 25% of the vapour pressure of free gamma benzene hexachloride. For example, it has been found that the water dispersible pulverulent compositions can have a composition wherein in said admixture the ratio of gamma benzene hexachloride to resin is such that the vapour pressure of the gamma benzene hexachloride is less than 20% of the vapour pressure of free gamma benzene hexachloride and after 6% has evaporated at 50° C. the vapour pressure is less than 8% of the vapour pressure of free gamma benzene hexachloride.

According to the present invention a water dispersible pesticidal pulverulent composition comprises an admixture containing gamma benzene hexachloride and at least one resin in intimate association wherein the ratio of gamma benzene hexachloride to resin is such that for

2

vapour pressures measured by effusion at 50° C. the vapour pressure of the gamma benzene hexachloride is less than 75% of the vapour pressure of free gamma benzene hexachloride and after 25% has evaporated at 50° C. the vapour pressure is less than 25% of the vapour pressure of free gamma benzene hexachloride.

By way of example said water dispersible pesticidal pulverulent composition can be one wherein in said admixture the ratio of gamma benzene hexachloride to resin is such that for vapour pressures measured by effusion at 50° C. the vapour pressure of the gamma benzene hexachloride is less than 20% of the vapour pressure of free gamma benzene hexachloride and after 6% has evaporated at 50° C. the vapour pressure is less than 8% of the vapour pressure of free gamma benzene hexachloride.

Because the aforesaid admixtures in the aforesaid water dispersible pesticidal compositions have a vapour pressure less than 25% of free gamma benzene hexachloride only after 25% has evaporated at 50° C., or, for example a vapour pressure less than 8% of free gamma benzene hexachloride only after 6% has evaporated, it is assumed, because rate of evaporation is a function of vapour pressure, that the rate of evaporation of the gamma benzene hexachloride in said water dispersible pesticidal composition will be less than the rate of evaporation of free gamma benzene hexachloride.

Said water dispersible pesticidal pulverulent compositions may be pulverulent compositions of a powdered solidified melt of an admixture comprising gamma benzene hexachloride and at least one resin in the aforesaid ratios.

The preferred resins are solid chlorinated paraffins, for example the solid chlorinated paraffin waxes and in particular the solid chlorinated paraffin wax "Cereclor" 70. "Cereclor" is a registered trademark. "Cereclor" 70 is a solid chlorinated paraffin wax having an average chlorine content of 70%, a freezing point of between 70 and 80° C. and a specific gravity of 1.63.

Satisfactory results have been obtained on sorptive and non sorptive surfaces from pesticidal pulverulent compositions which contained gamma benzene hexachloride to a solid chlorinated paraffin wax containing 65-75% chlorine, for example "Cereclor" 70, in a 3:1 ratio but the best results have been obtained from pesticidal pulverulent compositions wherein the ratio of gamma benzene hexachloride to a solid chlorinated paraffin wax containing 65-75% chlorine, for example "Cereclor" 70, has been not higher than 2:1 and often when said ratio is not much higher than 1:1. In other words, although satisfactory results have been obtained on sorptive as well as non sorptive surfaces when the gamma benzene hexachloride did not exceed 75% by weight on the combined weight of the gamma benzene hexachloride and the solid chlorinated paraffin, particularly a solid chlorinated paraffin wax containing 65-75% chlorine, for example "Cereclor" 70, it is often preferred for the gamma benzene hexachloride not to exceed 55% by weight on the combined weight of the gamma benzene hexachloride and the solid chlorinated paraffin, particularly a solid chlorinated paraffin wax containing 65-75% chlorine, for example "Cereclor" 70.

Examples of water dispersible pesticidal pulverulent compositions according to the invention are those comprising a solid chlorinated paraffin, as for instance a solid chlorinated paraffin wax, particularly "Cereclor" 70, and gamma benzene hexachloride wherein the gamma benzene hexachloride does not exceed 75% by weight, and, for instance, does not exceed 50% by weight on the combined weights of the solid chlorinated paraffin, or for instance, the solid chlorinated paraffin wax, and the gamma

benzene hexachloride. These water dispersible pesticidal pulverulent compositions may contain diluents as for example a china clay and various dispersing and wetting agents as for instance formaldehyde naphthalene sulphonate acid condensation products and salts of alkyl naphthalene sulphonate acids.

Examples of water dispersible pesticidal pulverulent compositions according to the invention are

	Percent
Gamma benzene hexachloride/"Cereclor" 70 (3:1) or gamma benzene hexachloride/"Cereclor" 70 (2:1) or gamma benzene hexachloride/"Cereclor" 70 (1:1)	50
Fuller's earth	40
A sodium alkyl aryl sulphonate	8
A sodium alkyl naphthalene sulphonate	2

The 3:1 and 2:1 gamma benzene hexachloride/"Cereclor" 70 pulverulent compositions were found to pass the World Health Organisation suspensibility test after storing for 24 hours at 55° C. under pressure as specified by the World Health Organisation giving suspensibilities of 60% (3:1) and 54% (2:1) respectively, the test limit being 50%. This suspensibility test is carried out as follows: Sufficient powder to give 250 ml. of a suspension containing 0.5% gamma BHC is weighed accurately. It is pasted with 30 ml. hard water and allowed to stand at 30° C. for 15 minutes. The slurry is rinsed into a 250 ml. measuring cylinder with water at 30° and the cylinder is filled to the 250 ml. mark. After being inverted through thirty complete cycles the suspension is allowed to stand for exactly half an hour when the top nine-tenths of the suspension is sucked off. The BHC remaining in the 25 ml. residue is determined by any convenient method. The suspensibility is given by the following equation.

$$\text{Percent suspensibility} = \frac{(b-a) \times 10 \times 100}{b \times 9}$$

where

a =weight of gamma BHC found in the remaining one-tenth of the suspension.

b =weight of gamma BHC in the sample used for the test.

Tables 1 and 2 are a record of the vapour pressure results at 50° C. which are obtained for gamma benzene hexachloride and gamma benzene hexachloride/resin mixtures after stated percentage evaporations in an effusion apparatus which is essentially similar to that described by Small, Small and Cowley (Trans. Faraday Soc., 1948, 44, 810) and in which the diameter of the bulb is about 10 mm. and that of the hole in the bulb is 2.4 mm. Table 1 shows the effect of different amounts amounts of "Cereclor" 70 to gamma benzene hexachloride on the vapour pressure of gamma benzene hexachloride and Table 2 shows the effect of various resins in a 3:1 ratio of gamma benzene hexachloride to resin.

Table 1

Sample	Initial vapour pressure, mm.	Vapour Pressure Relation to Percent Evaporated	
		mm. Hg at 50° C.	Percent evaporated at 50° C.
Gamma benzene hexachloride alone	9.3×10^{-4}	9.3×10^{-4}	71 (calculated)
Gamma benzene hexachloride/"Cereclor" 70: 9:1	10.7×10^{-4}	5.9×10^{-4}	42
3:1	6.6×10^{-4}	1.9×10^{-4}	24
2:1	6.4×10^{-4}	1.8×10^{-4}	23
1:1	1.7×10^{-4}	0.7×10^{-4}	4
"Cereclor" 70	$<0.7 \times 10^{-4}$	0.5	(calculated)

Table 2

Sample	Initial vapour pressure, mm.	Vapour Pressure Relation to Percent Evaporated	
		mm. Hg at 50° C.	Percent evaporated at 50° C.
"Aroclor" 5460 (a chlorinated polyphenol)	7.9×10^{-4}	3.5×10^{-4}	34
A para tertiary octyl phenol resin	6.4×10^{-4}	2.7×10^{-4}	35
A coumarone resin, M.P. 75-85° C.	6.2×10^{-4}	3.4×10^{-4}	41
A phenolic terpene resin	5.6×10^{-4}	2.8×10^{-4}	29
A modified phenolic terpene resin	5.4×10^{-4}	2.0×10^{-4}	33

From a comparison of the data in Tables 1 and 2 it is seen that for a 3:1 gamma benzene hexachloride/resin mixture the gamma benzene hexachloride/"Cereclor" 70 composition gives the best results and from a study of Table 1 it is seen that it is desirable not to go beyond a 3:1 gamma benzene hexachloride/"Cereclor" 70 composition and that a 1:1 gamma benzene hexachloride/"Cereclor" 70 composition has the stipulated physical characteristics of a pulverulent composition of the invention required for extreme persistence of deposits of gamma benzene hexachloride.

Also from pesticidal persistence tests carried out on surfaces of glass, filter paper and plaster of Paris with gamma benzene hexachloride and various resins and with different ratios of gamma benzene hexachloride to the various resins it has been deduced that the most satisfactory dispersible pesticidal pulverulent compositions for filter paper and plaster of Paris surfaces are those containing gamma benzene hexachloride and a solid chlorinated paraffin wax, particularly "Cereclor" 70 and wherein the ratio of gamma benzene hexachloride to "Cereclor" 70 is not greater than 3:1.

Again from cooling curve tests of melts of gamma benzene hexachloride and "Cereclor" 70 mixtures it has been ascertained that whereas for 2:1 and 3:1 ratios of gamma benzene hexachloride to "Cereclor" 70 mixtures there are well defined regions where the gamma benzene hexachloride crystallises out there is no such well defined region for mixtures up to a 1:1 ratio of gamma benzene hexachloride to "Cereclor" 70.

A determination of the persistence of dispersible powder gamma benzene hexachloride formulations were carried out as follows.

Solid solutions were made by fusing gamma benzene hexachloride with beta-naphthyl glycide ether, "Aroclor" 5460 and "Cereclor" 70. The resultant solids were ground and formulated by milling with china clay as diluent, sodium naphthalene formaldehyde sulphonate and a sodium alkyl naphthalene sulphonate to give water dispersible powders containing 50% organic component. Powders containing gamma benzene hexachloride and beta-naphthyl glycide ether in 2:1 and 1:1 ratios gave no increase in persistence on plaster of Paris surfaces after gamma benzene hexachloride dosages of 10 or 20 mg./sq. ft. Powders containing "Aroclor" 5460 or "Cereclor" 70 with gamma benzene hexachloride gave striking increases in persistence when tested on filter paper, and the "Cereclor" 70 formulations also had high persistence on plaster of Paris, a relatively non-sorptive surface.

Table 3 is a record of the time of exposure in minutes required to give a 50% knock-down of *M. domestica* as estimated from each graph which is obtained by plotting probit of percent knockdown against contact period in minutes for airing periods respectively of 1, 32, 60, 90 and 120 days with plaster of Paris test pieces treated with the dispersible powders gamma benzene hexachloride, fused gamma benzene hexachloride/"Cereclor" 70 (1:1), fused gamma benzene hexachloride/"Cereclor" 70 (2:1), fused gamma benzene hexachloride/"Aroclor" 5460 (2:1)

and fused gamma benzene hexachloride/"Aroclor" 5460 (3:1) at 10.2 mg. gamma benzene hexachloride/ft.².

Table 3

Powder	Surface	Exposure (min.) required to give 50% knock-down of <i>M. domestica</i> after . . . days airing				
		1	32	60	90	120
gamma benzene hexachloride.	Plaster of Paris.	44	170	91	2,692	1,660
gamma benzene hexachloride/"Cereclor" 70 (1:1).	do.	118	50	31	72	398
gamma benzene hexachloride/"Cereclor" 70 (2:1).	do.	55	50	32	102	295
gamma benzene hexachloride.	do.	44	178	85	2,951	1,778
gamma benzene hexachloride/"Aroclor" 5460 (2:1).	do.	32	126	209	251	1,514
gamma benzene hexachloride/"Aroclor" 5460 (3:1).	do.	39	224	339	550	794

From the above table it will be seen that the gamma benzene hexachloride/"Aroclor" 5460 (2:1) dispersible powder is estimated to require a longer exposure time than the gamma benzene hexachloride/"Cereclor" 70 (2:1) dispersible powder for 50% knockdown of *M. domestica* at every airing period apart from the first (one day).

The effect of "Cereclor" 70 on increasing gamma benzene hexachloride persistence against a strain of the mosquito *Anopheles gambiae* Giles was determined as follows. Sorptive mud blocks made from red lateritic soil from Babati and Tanganyika, 3 inches in diameter, were treated by pipette with aqueous suspensions of insecticide and the mosquitos exposed in "Pespex" chambers to the residues. *Anopheles gambiae* Giles is a resistant strain of mosquito and was chosen for these experiments in order to accelerate the test.

Groups of approximately 20 mosquitoes, of mixed sex, 1-2 days old, were used for each test, the exposure period (2-8 hours) being determined by the age of the residue.

All tests were carried out under constant temperature and humidity conditions (25° C. and 70% relative humidity). The blocks were stored under these conditions, the same blocks being used in successive tests.

Table 4 shows a comparison of the persistence of gamma benzene hexachloride with and without "Cereclor" 70 (1:1) at 50 mg./square foot on sorptive mud against *Anopheles gambiae* Giles (expressed in terms of percentage mortality).

Table 4

Age of residue (days)	11	34	38	39	46	60
Exposure period (hr.)	2	3	5	8	8	8
Gamma-BHC	89	89	10	0	6	5
Gamma-BHC-"Cereclor" 70	89	88	80	55	44	59

What we claim is:

1. A water dispersible pesticidal pulverulent composition comprising a solid solution of gamma benzene hexachloride dissolved in solid chlorinated paraffin having an average chlorine content of about 70%, a freezing point between about 70 and 80° C. and a specific gravity of about 1.63 and in intimate association therewith characterized in that the pulverulent composition is water dispersible and in that the ratio of gamma benzene hexachloride to chlorinated paraffin in the admixture is such that for vapor pressures measured by effusion at 50° C. the vapor pressure of the gamma benzene hexachloride is less than 75% of the vapor pressure of free gamma benzene hexachloride and after 25% has evaporated at 50° C. the vapor pressure is less than 25% of the vapor pressure of free gamma benzene hexachloride.

2. A water dispersible pesticidal pulverulent composi-

tion as claimed in claim 1 wherein in said admixture the ratio of gamma benzene hexachloride to chlorinated paraffin is such that the vapour pressure measured as aforementioned of the gamma benzene hexachloride is less than 20% of the vapour pressure of free gamma benzene hexachloride and after 6% has evaporated at 50° C. the vapour pressure is less than 8% of the vapour pressure of free gamma benzene hexachloride.

3. A water dispersible pesticidal pulverulent composition as claimed in claim 1 wherein in said admixture the gamma benzene hexachloride and chlorinated paraffin in intimate association and in the aforesaid ratio are in the form of a powdered solidified melt of an admixture thereof.

4. A water dispersible pesticidal pulverulent composition as claimed in 1 wherein the gamma benzene hexachloride does not exceed 75% by weight on the combined weight of the gamma benzene hexachloride and the solid chlorinated paraffin.

5. A water dispersible pesticidal pulverulent composition as claimed in claim 4 wherein the gamma benzene hexachloride does not exceed 55% by weight on the combined weight of the gamma benzene hexachloride and the solid chlorinated paraffin.

6. A water dispersible pesticidal pulverulent composition as set forth in claim 1 in which the benzene hexachloride is present in the amount not greater than about 3 times the amount of said chlorinated paraffin.

7. The method of treating a sorptive surface with a pesticidal pulverulent composition which comprises applying to the sorptive surface a water dispersion of a composition comprising a solid solution containing gamma benzene hexachloride dissolved in solid chlorinated paraffin having an average chlorine content of about 70%, a freezing point between about 70 and 80° C. and a specific gravity of about 1.63 and in intimate association therewith characterized in that the pulverulent composition is water dispersible and in that the ratio of gamma benzene hexachloride to chlorinated paraffin in the admixture is such that for vapor pressures measured by effusion at 50° C. the vapor pressure of the gamma benzene hexachloride is less than 75% of the vapor pressure of free gamma benzene hexachloride and after 25% has evaporated at 50° C. the vapor pressure is less than 25% of the vapor pressure of free gamma benzene hexachloride.

8. A water dispersible pesticidal pulverulent composition comprising a solid solution of gamma benzene hexachloride dissolved in solid chlorinated paraffin having an average chlorine content of about 65-75%, a freezing point between about 70 and 80° C. and a specific gravity of about 1.63 and in intimate association therewith characterized in that the pulverulent composition is water dispersible and in that the ratio of gamma benzene hexachloride to chlorinated paraffin in the admixture is such that for vapor pressures measured by effusion at 50° C. the vapor pressure of the gamma benzene hexachloride is less than 75% of the vapor pressure of free gamma benzene hexachloride and after 25% has evaporated at 50° C. the vapor pressure is less than 25% of the vapor pressure of free gamma benzene hexachloride.

9. The method of treating a sorptive surface with a pesticidal pulverulent composition which comprises applying to the sorptive surface a water dispersion of a composition comprising a solid solution containing gamma benzene hexachloride dissolved in solid chlorinated paraffin having an average chlorine content of about 65-75%, a freezing point between about 70 and 80° C. and a specific gravity of about 1.63 and in intimate association therewith characterized in that the pulverulent composition is water dispersible and in that the ratio of gamma benzene hexachloride to chlorinated paraffin in the admixture is such that for vapor pressures measured by effusion at 50° C. the vapor pressure of the gamma benzene hexachloride is less than 75% of the vapor pressure of free gamma benzene hexachloride and after 25%

has evaporated at 50° C. the vapor pressure is less than 25% of the vapor pressure of free gamma benzene hexachloride.
